CLAIM

The ornamental design for a laptop computer, as shown and described.

DESCRIPTION

1.,3. Laptop computer
1.1 : Front
1.2 : Back
1.3 : Left
1.4 : Enlarged
1.5 : Right
1.6 : Top
1.7 : Bottom
3.1 : Front
3.2 : Back
3.3 : Left
3.4 : Enlarged
3.5 : Right
3.6 : Top
3.7 : Bottom
3.8 : Perspective

The design shown in FIGS. 1.1 through 1.7 discloses the laptop computer in a closed state and the design shown in FIGS. 3.1 through 3.8 discloses the laptop computer in an opened state. The broken lines shown in the drawings illustrate portions of the laptop computer that form no part of the claimed design.

1 Claim, 15 Drawing Sheets
